UNITED STATES PATENT OFFICE

THOMAS EDGAR PERKS, OF AUCKLAND, NEW ZEALAND

SEPARATION, BY DISTILLATION, OF MISCELLANEOUS LIQUIDS

Application filed November 3, 1927, Serial No. 230,853, and in New Zealand April 26, 1927.

This invention has reference to a process whereby materials composed of mixtures of liquids having different boiling points, or which vaporize at different degrees of temperature, may be treated to separate and recover the different liquids, or to separate from the original mixture fractions of desired boiling range. It also has reference to a special form of apparatus for use in carrying out the 10 said process.

The invention has particular application to the treatment of petroleum oils or mixtures of oils for the purpose of separating the component oils of different grades or specific 15 gravities, and may also be used with beneficial effect in the treatment of petroleum oils containing foreign matters for the separation and purification of the valuable constituents thereof.

20 The said process consists in the submission of the material to a progressive heating action while it is caused to flow in a continuous passage and to the separate collection, at different points in such flow, of the vapours produced by the boiling of the portions of such material at such different points, and in the subsequent condensation of such vapours.

In giving effect to such process the material to be separated into appropriate liquid 25 fractions of different boiling points or ranges of boiling points, is caused to flow in a continuous stream through an apparatus, where in the temperature of such mixture is progressively raised with the object of bringing 30 to their boiling points the various components of the mixture at appropriate parts of the apparatus. The vapours so formed are trapped in suitable vapour zones and in these zones are condensed and led as liquids to their 35 several containers. Provision may be made in such zones for additional purification either by the usual scrubbing, i. e. reflux flow, or more simply by suitable arrangement of collecting trays at such position in the zones as 40 to ensure the return either to the liquid stream for reheating or to previous collecting trays of such condensed vapours as may more properly belong to other zones.

It is essential in giving effect to such process 45 that the liquid to be separated into its de-

sired fractions should flow continuously in a channel having a free vapour space above it and that the progressive heating should take place during its passage along this channel. Also that the free vapour space should be 55 divided into vapour zones at appropriate points for the separation of the vapours in the desired manner and such divisions so arranged that the vapours go direct to the zones intended without passing through any other 60 zone in doing so.

Since the vapours pass directly and freely into the zones appropriate to them and are thus separated without the necessity of employing reflux flow or otherwise opposing by 65 means of a liquid head their free passage, there is no back pressure and the process is therefore particularly suited to vacuum distillation.

This taking of the vapours directly to the 70 zone required means a minimum of heat required for the work as there is no back pressure caused by one fraction having to drive another as is the case in standard fractionating towers.

75 Further the principles above ensure that cracking of an oil is reduced to a minimum as the vapours are immediately removed from the liquid and cannot fall back on that liquid at a point where the liquid is at a 80 higher temperature than that at which the particular fraction boils.

The said process may be carried out in any suitable form of apparatus providing for the 85 flowing of the liquid in a continuous course beneath a series of separate vapour collecting zones, each of which has its condensing means combined therewith and also has provision for the collection and draining away of the condensed vapour.

90 Apparatus of suitable design is shown in the accompanying drawings, in which:—

Figure 1 is a perspective sketch of one form of apparatus.

Figure 2 is a sectional plan of the upper, or 95 vapour zone, portion of such apparatus.

Figure 3 is a plan of the lower, or liquid containing, portion of the apparatus.

Figure 4 is a cross sectional elevation 100 thereof.

Figure 5 is a sectional elevation of an alternative form of apparatus.

Figure 6 is a plan thereof taken on the line 6—6 of Figure 5.

5 In the form of apparatus shown in Figures 1 to 4, a bottom chamber 10 (Figure 3) of rectangular form is provided, and divided by plates 11 into a passage 12 extending in zig-zag fashion across it from one end to the other so that a continuous course is thus provided. An inlet pipe 13 leads into one end of this passage and an outlet 14 leads away from its other end.

15 Arranged beneath the bottom of this chamber are a number of heating elements, as the gas burners 15, which are directed to heat the liquid passing along the course 12 and to progressively raise it in temperature as it passes from one end to the other.

20 Fixed above the open top of the chamber 10 is an upper chamber 16 which is enclosed on its sides, ends and top and fully open at its bottom to the lower chamber 10. This chamber 16 along the inside of each side, is formed with an elevated channel and each channel is divided by the vertical plates 18 extending to the top of the chamber, into a number of separate collecting trays 17, with those on one side arranged respectively opposite to those on the other. The central part of the space enclosed by the chamber is divided by the transversely extending and vertically disposed plates 19 into a number of separate divisions which form the vapour collecting zones 20. These plates 19 are disposed to extend coincidentally with the plates 18 and rest upon the lower chamber 10 and extend to the top of the chamber 16 in order thus that each zone 20 is quite separate from the others and has its two collecting trays 17.

45 The vapour thus given off from the liquid passing along the course 12, while travelling beneath each zone, is caught within such zone and by cooling and condensation collects within the trays 17 of that zone and is drawn off therefrom. This is done preferably through an outlet 21 leading from one tray, the tray on the other side draining through the pipe 22 into the first mentioned tray.

55 The cooling of the vapours is effected by making the side walls of the chamber 16 with jacket spaces 23 and by leading a supply of cooling medium (as cold water) through these spaces, such medium being led in through the inlet 24 and carried away through the outlet 25.

60 The respective outlets 21 are led to the desired receptacles and such receptacles are preferably connected with air exhaustion means so that they are in vacuum, or partial vacuum, and thereby ensure of the rapid withdrawal of the condensations from the respective zones.

65 The number of zones will be determined

by the number of grades into which it is desired to separate the material being treated and such division is effectually obtained by the proper controlling of the heating means to heat such material to the necessary stage to provide for the vapourization of the different constituents as the material travels beneath the said zones. 70

The material is caused to travel through the passage 12 by gravitation or other force, 75 the unvapourized portion and sludge or foreign matters being drawn off through the outlet 14 into a receptacle which also may be under vacuum conditions.

The apparatus shown in Figures 5 and 6 is 80 built and works upon the same lines. In this case however, the apparatus is generally of cylindrical or circular form, and the lower chamber 10' has its course 12' made to extend in a spiral guided by partitions 11' from the 85 outer edge into the centre. The outlet 14' then opens downward from such center and the inlet is indicated by pipe 13'. The heaters (not shown) for this apparatus are disposed to heat the material progressively as 90 it travels to the said centre.

The upper chamber 16' is divided into the required number of separate zones 20' by means of the concentrically arranged cylinders 26 which by being arranged above the 95 passage 12' provide the separate vapour collecting spaces.

A more effective separation of the zones with respect to the liquid course may be obtained by forming the latter also of concentric rings instead of the spiral. In this case each circular space is blocked at about a full circumferential travel from the inlet and then opens into the next inner space to cause the continuous and in effect, spiral course. 100

The collecting tray 17' for each zone is arranged to extend around the outer edge thereof by being attached to the appropriate cylinder at an approved elevation in the zone, the vapour passing upward into the top of the zone around the inner edge of the tray. A deflecting plate 27 is provided over the said vapour passage to prevent the condensed liquid dripping back into the bottom chamber by causing such to be deflected into the tray. 110

In this case the cooling is effected by means of a circulating pipe system 28 arranged around the outer wall of each zone and through which the desired cooling medium is passed. 115

Each tray 17' is provided with a drain pipe 21' leading away therefrom and which may be under vacuum action, as in the previous case. Or, if desired, the vacuum conditions within the apparatus may be obtained by providing a space 29 within the top of the chamber 16, from which a pipe 30 leads away to exhaustion apparatus. 120

I claim:—

An apparatus for the separation of mis- 130

cible liquids, comprising a primary receptacle with open top, partitions in said receptacle providing a zig-zag passage therethrough, an inlet pipe opening into one end of said passage and an outlet pipe opening at the opposite end of the passage, means for heating said receptacle; a second receptacle with open bottom adapted to register with said open top, suitable partitions dividing said second receptacle into side channels and central vapor collecting zones, the partitions of said zones registering with the partitions of said passage, a collecting tray in each of said channels for the respective zones, means for passing a cooling medium outwardly and alongside of said channels and a pipe for draining off the condensate collected in each of said trays.

In testimony whereof, I affix my signature.
